United States Patent Office.

MRS. RUTH ANN N. ATWOOD WARD, OF PHILADELPHIA, PENNSYLVANIA.

Letters Patent No. 82,901, dated October 6, 1868.

IMPROVEMENT IN BRACE AND SKIRT-SUPPORTER COMBINED.

The Schedule referred to in these Letters Patent and making part of the same.

TO ALL WHOM IT MAY CONCERN:

Be it known that I, RUTH ANN N. ATWOOD WARD, of city and county of Philadelphia, and State of Pennsylvania, have invented a new and useful Improvement in Shoulder-Braces and Skirt-Supporters; and I do hereby declare the following to be a full and correct description of the same, sufficient to enable others skilled in the art to which my invention appertains to fully understand and construct the same, reference being had to the accompanying drawings, which make part of this specification, in which—

Figure 1 is a rear view of my improved brace and supporter as worn on the person, and

Figure 2 is a view, showing the front part and its attachment.

Like letters of reference indicate like parts in the two figures.

The nature of my invention consists in the peculiar construction of a brace and skirt-supporter, whereby I do away with the wearing of corsets, and at the same time form a convenient means of supporting the skirt. *a*, in fig. 2 of the drawings, represent pieces to which are attached straps, *b*, of belting, which pass over the shoulder, and at *c* connect with other straps of belting, *d e f*, and an elastic strap, *g*.

The straps *d* are connected to the pieces *a* by means of short elastic straps *h*. The straps *e* extend straight downwardly, and form a continuation of straps *b*. Straps *f* extend downward under the arm, passing to the front, where its bight, *f'*, buckles in the double-ended buckle-strap *i*, and passing upward forms a loop, *j*, around a short elastic strap, *k*, which connects the belting-strap *l* to the lower end of piece *a*. The strap *l* passes through a loop, *l'*, on strap *f*, and, passing over straps *e* and *d* on the back, buckles into an elastic buckle-strap attached to the other piece *a* and strap *f*.

The free ends of straps *d* and *e* buckle into buckle-straps, *m*, provided, as well as buckle-straps *i*, with buttons, by means of which to secure loops *n* on the skirt-band *o*, or the buttons may button into button-holes on the band *o*.

There are three distinct lines of bracing in my improved brace and supporter. The first is by the straps *e b*, piece *a*, straps *k* and *l*, and it serves to throw the upper portion of the upper part of the body, that is breast, shoulders, and neck, well out. The second line is by straps *d h*, piece *a*, straps *k* and *l*, and it serves to throw back the shoulders, and to prevent stooping. The third line is by straps *b h*, piece *a*, straps *k, f, l*, and *g*, and this serves to balance the other two lines of bracing, and to support the back in place of a corset. And whereas a corset, being comparatively stiff and unyielding, while supporting the body, prevents its free movement, my brace allows every muscle of the upper part of the body its full free play, and yet supports the same firmly, the elastic straps *g h k* allowing the brace to conform itself to the body, without yielding more than is necessary, and at the same time supporting the skirt or skirts, which thus need not to be tied around the waist, this tight tying being, as is well known, very injurious to the health.

The brace and supporter can be made in all sizes to suit persons of different age and stature, and is easily adjusted by the wearer to the body by means of strap *l* and the buckling-straps *d e f*.

Having thus described my invention, what I claim as new, and desire to secure by Letters Patent, is—

The improved brace and supporter consisting of pieces *a*, straps of belting *b, d, e, f*, and *l*, buckle-straps *i* and *m*, and elastic straps *g h k*, when arranged to operate for bracing and supporting, substantially as described.

To the above I have signed my name, this eleventh day of September, 1868.

MRS. RUTH ANN N. ATWOOD WARD.
